UNITED STATES PATENT OFFICE.

JOHANNES TH. PEDERSÉN, OF WOODSIDE, NEW YORK.

DENTAL HANDPIECE.

SPECIFICATION forming part of Letters Patent No. 577,063, dated February 16, 1897.

Application filed January 6, 1896. Serial No. 574,423. (No model.)

To all whom it may concern:

Be it known that I, JOHANNES THEODOR PEDERSÉN, a citizen of the United States, residing at Woodside, in the county of Queens 5 and State of New York, have invented a new and useful Improvement in Dental Handpieces, of which the following is a specification.

My present invention is designed as an improvement upon the device shown and described in Letters Patent granted to me January 7, 1896, No. 552,669. In said patent the pressure endwise that causes the tool-holder to grasp the tool is derived principally from 15 a toggle movement.

In my present invention, as in the aforesaid patent, I employ a handpiece wherein the tool is held by the internal mechanism in the straight normal condition and released 20 by a direct lateral pressure of one hand upon the handpiece while holding the same, which pressure deflects the parts and alters the alinement of one part to the other and produces an elongation, which releases the grip 25 upon the tool, said grip being restored by the return of the parts to a normal condition. In the present instance the tool-holder is released or drawn backward by a positive movement, and a spring is employed to press the tool-holder forward as it grasps the tool, and the exterior case is made of two principal parts, the lower end of which is adapted to being 30 grasped by the hand, and the upper end is provided with an adjustable tubular case 35 surrounding a helical spring, by the adjustment of which more or less tension can be applied to the spring, and when the upper part of the case is swung or deflected at an angle to the lower part of the case, the tubular case 40 around the spring causes such spring to be distended, and hence the parts are returned to a normal position with a rapid positive movement the moment the deflecting pressure 45 is released, thus facilitating the handling of the tool.

The helical spring and the end collars connected therewith form the flexible part of the case, and the tubular case surrounding the spring bears at one end on the forward collar 50 to form a fulcrum when the case is swung to release the tool. In the internal mechanism there are bearing or cam surfaces that move

upon each other as the parts are swung out of alinement, and an elongation is produced that releases the spring tool-holder and allows 55 the same to open and release the tool.

The details of construction are hereinafter more particularly described and claimed.

In the drawings, Figure 1 is a longitudinal section of my improved dental handpiece. 60 Fig. 2 is an elevation of the same. Figs. 3 to 15, inclusive, represent elevations of the separate parts of the internal mechanism, and Fig. 16 is a partial longitudinal section of the internal parts as deflected. The figures show the parts of about twice the usual size.

The case of my dental handpiece is preferably composed of the rigid taper portion A, whose exterior is preferably roughened or 70 ribbed to provide a firm hold for the hand, and the upper portion B of the case comprises the tubular case l, the helical spring a, the collar a', and screw-collar a''. The collar a' receives within it one end of the helical 75 spring a, and the other end of said spring extends over the forward end of the collar a'', and the ends of the spring a are firmly united by solder to the collars a' and a''.

The collar a' is united by a screw-coupling 80 at 2 to the taper portion A, and the back end of the collar a'' is threaded and projects for receiving the sleeve at the end of the flexible covering for the shaft of the dental engine, and the tubular case l has a nut at one end 85 which screws upon the collar a'' and surrounds the spring a and extends into the enlarged end of the collar a', and the end of said case l bears against said collar, and the said tubular case l can be screwed along upon the collar a'' to strain the helical spring a and apply 90 any desired tension thereon. The case l also protects the hand from contact with the spring a and acts to exclude dust from the internal parts.

Figs. 3 and 4 show separately the sleeves b b', that screw together and are received within the rigid taper-case A. The right-hand or back end of the sleeve b' is reduced, and a hard-metal collar b'', fitting over said end, is 100 held between the end of the case A and an internal rib on the collar a', and this collar b'' forms a stop around the back end of the sleeve b', thus holding the sleeves b b' within 95

the tubular case and preventing end motion, but allowing them to be revolved freely. The clamping-nut *g* prevents the collar *a'* turning and secures the parts after they have been 5 adjusted.

The forward end of the sleeve *b* is tapering to conform to the interior of the case *A*, and it is also internally tapered to act on the holding-jaws *d'*, Fig. 5, and these jaws receive and 10 hold the tool. These jaws *d'* are made with an open center to receive the tool, and the longitudinal slots between the jaws allow them to spring, and they are tapered at both ends, the forward ends being received into 15 the tapering sleeve *b* and the back ends into the recessed forward end of the sleeve *e'*, Figs. 1 and 7. The adjusting-stem *f* has a threaded portion 12 and screws into the split end of the sleeve *e'*, Figs. 1 and 7. This stem 20 *f* has a screw-driver notch 13 at one end.

The rod *h* from the dental-engine shaft is connected by a pin 17 with the collar *c'*. A screw stem or rod *n* is provided with a head *n'* and adjacent neck, there being a flaring 25 hole through the head *n'*. This head is received within the collar *c'*, behind the internal rib 11, and a pin 16 passes through the flaring hole and connects the head and collar together, and the end of the collar *c'* is provided with curved bearing-faces 19. A head-block *o*, that surrounds the rod *n*, is provided with curved bearing-faces 18, receiving or coming against the faces 19, and the block *o* fits into and bears against the end of the 30 sleeve *b'*. This rod *n* screws into the sleeve *m* and around the rod *n* within the sleeve *b'*, and between the sleeve *m* and inner end of the sleeve *b'* and the block *o* is the expansive spring *k*, whose action is to force the sleeve 35 *m* forward, and so hold the faces 18 and 19 tightly together and the parts axially in line, the head *n'* bearing against the rib 11. The opposite ends of the sleeves *m* and *e'* are notched, and the ends of the thrust-piece *r* 40 are reduced to form tongues that are received in said notches, the tongues at one end bearing against the threaded stem *f*, and the other tongue is notched to receive and bear against the reduced end of the rod *n*.

50 The parts are put together in approximately the following manner and order: The rod *n* and collar *c'* are connected by the pin 16, with the head *n'* bearing against the rib 11 from within, and the rod *h* and collar *c'* are connected together by the pin 17. The head-block *o* is slipped over the rod *n* and the ring *b*² over the end of the sleeve *b'*, and then the sleeve *b'* and ring *b*² are passed over the rod *n* and block *o*. The spring *k* is passed into the sleeve 55 *b'* and over the rod *n*, and the sleeve *m* screwed on the rod *n* to compress the spring *k* and draw the parts together. The screw-stem *f* is inserted in the sleeve *e'*. The tool-holder *d'* is now inserted in the sleeve *b*, and the sleeve *e'* 60 and thrust-piece *r* inserted therein, following the tool-holder. The sleeves *b* and *b'* are brought together with the ends of the thrust- 65

piece in the notches of the sleeves *e'* and *m*, and they are screwed together. A screw-driver can be inserted in place of an operating-tool, and it engages the stem *f* at its notch 13, and by rotating said stem in the sleeve *e'* the parts are adjusted in their axial line to provide for slight variations in the diameters of the tool-shanks, so as to bring sufficient 70 pressure by the holding-jaws to grip the operating-tool *C*. This adjustment also provides for wear of the parts. The flexible dental-engine shaft rotates the rod *h* and the parts within the connected cases *A* and *B* that extend from such shaft to the tool-holder. 75

To release the operating-tool from the grip of the holding-jaws, it is only necessary to bring one part of the case at an angle to the other part and thereby produce an elongation 80 of the axis of the handpiece. This is accomplished by one hand, while holding the handpiece, by a pressure of the thumb and fingers bending the helical spring *a* out of line with the tapering case *A*. When the handpiece is 85 thus deflected in the hand, the end of the tubular case *l* rocks upon the collar *a'* as a fulcrum, the helical spring *a* is bent and distended, and the rod *h* is swung into approximately the position shown in Fig. 16. This 90 operation disturbs the alinement of the internal mechanism and causes the curved bearing-face 19 of the collar *c'* to move upon the curved bearing-surface 18 of the head-block *o* and so draw the rod *n* and head *n'* and sleeve 95 *m* longitudinally, compressing the spring *k* and releasing the parts *r e'*, so that the tool-holder is free to expand and release the tool. 100

When the pressure of the hand is released, the spring returns the parts to their normal 105 positions of alinement, and by this movement the pressure upon the holding-jaws is restored and the operating-tool firmly gripped by the tool-holder.

It is obvious that suitable equivalent means 110 may be employed to connect the head *n'* or rod *h*, or both of them, to the collar *c'* to cause the said parts to rotate together.

I claim as my invention—

1. The combination in a dental handpiece, 115 of a case adapted to being held in the hand, a tool-holder within the case, a driving-shaft adapted to being connected to the flexible shaft of the dental engine, an internal spring surrounding a portion of the driving-shaft 120 for giving end movement to the tool-holder to grasp the tool, and devices having opposing curved bearing-faces adapted to rock on one another and acting to compress the spring and positively move a portion of the driving-shaft longitudinally to remove the pressure 125 on the tool-holder and permit the same to expand and release the tool when the rear part of the shaft is swung or deflected, substantially as set forth. 130

2. The combination in a dental handpiece, 130 of a case adapted to be grasped by the hand, a spring connected with the rear end of such case, a tubular case surrounding the spring,

and bearing at one end against the rear end of the case whereby the spring is distended when the rear part of the case is deflected out of line with the hand portion of the case and such tubular case is restored into line with the case by the action of the spring, substantially as set forth.

3. The combination in a dental handpiece, of a case adapted to being grasped by the hand and having a collar at its rear end, a driving-shaft adapted to being connected to the flexible shaft of the dental engine, a screw-collar surrounding and sliding upon such shaft, a spring connected at one end with the screw-collar and at the other end to the collar of the handpiece, a tubular case around the spring with a nut at one end upon the screw-collar for adjusting the tension of the spring and devices having opposing curved bearing-faces for allowing the driving-shaft and tube to be turned or deflected into an angular position to the hand portion of the case and restored into line by the action of the spring, substantially as set forth.

4. The combination in a dental handpiece, of a case adapted to being grasped by the hand, a tool-holder to receive and grasp the tool by an end movement, a driving-shaft and an upper portion to the case around such driving-shaft and adapted to being deflected with that shaft into an angular position to the case, a connection from the driving-shaft to the tool-holder for rotating the same, an internal spring surrounding a portion of the driving-shaft for causing the tool-holder to grasp the tool and devices having opposing curved bearing-faces adapted to rock on one another and intervening between a portion of the driving-shaft and the spring for acting upon such spring to compress the same and to simultaneously and positively move a portion of the driving-shaft longitudinally to remove the pressure on the tool-holder and permit the same to expand and release the tool when the shaft is deflected, substantially as set forth.

5. The combination in a dental handpiece, of a case adapted to being grasped by the hand, a tool-holder to receive and grasp the tool by an end movement, a driving-shaft and an upper portion to the case around such driving-shaft and adapted to being deflected with that shaft into an angular position to the case, a connection from the driving-shaft to the tool-holder for rotating the same, an internal spring surrounding a portion of the driving-shaft for causing the tool-holder to grasp the tool and devices having opposing curved bearing-faces adapted to rock on one another and intervening between a portion of the driving-shaft and the spring for acting upon such spring to compress the same and to simultaneously and positively move a portion of the driving-shaft longitudinally to remove the pressure on the tool-holder and permit the same to expand and release the tool when the shaft is deflected, and an adjustment between

the tool-holder and the spring for varying the action and adapting the tool-holder to different sizes of tools, substantially as set forth. 70

6. The combination in a dental handpiece with the spring tool-holding jaws tapering at both ends, of a sleeve receiving the spring tool-holder, an internal sleeve adjacent to the rear end of the spring tool-holder, a threaded 75 adjusting-stem within the internal sleeve, a thrust-piece against which the adjusting-stem acts, the dental-engine shaft and mechanism intervening between the thrust-piece and such shaft for applying or relieving the pressure upon the thrust-piece, substantially as set forth.

7. In a dental handpiece, the combination with the rigid case A and collar a' having an internal rib, of the sleeve b' having a reduced 85 end, the hard-metal collar b² at the end of the case A and sleeve b' and between the same and the rib of the collar a', substantially as set forth.

8. In a dental handpiece, the combination 90 with the sleeve b' and the rod h from the dental-engine shaft, of the collar c', means for connecting the same to the rod h, the rod n, its head n' within the collar c' and a pin passing loosely through the head and into the collar 95 c' to connect said parts, a head-block o around the rod n, the collar c' and head-block o having adjacent curved bearing-faces whereby said rod h may be rocked or deflected from its axial line, and an end movement given to 100 the rod n, substantially as set forth.

9. In a dental handpiece, the combination with the sleeve b' and the rod h from the dental-engine shaft, of the collar c' connected to said rod h and having an internal rib 11 and 105 adjacent curved bearing-faces 19 at one end thereof, the rod n screw-threaded at one end and the sleeve m upon said threaded end, the head n' having a flaring hole and adjacent neck and bearing within the collar c' against 110 the rib 11, the pin 16 passing through said collar and head, the head-block o received within the end of the sleeve b' and having curved bearing-faces 18 that bear on the faces 19 and the helical expansion-spring k around 115 the rod n and acting against the sleeve m and inner end of the sleeve b' and block o to hold the faces 18 and 19 together tightly and the parts axially in line, substantially as set forth.

10. In a dental handpiece, the combination 120 with the sleeves b b' and the spring tool-holder d', of the notched sleeves e' and m, the threaded adjusting-stem f within the sleeve e' and having a screw-driver notch 13, the rod n threaded at one end and screwing into the 125 sleeve m, the thrust-piece r having reduced ends received within the notches of the sleeves e' and m and bearing at its ends upon the ends of the rod n and stem f respectively, the parts being adjusted longitudinally by the 130 rotation of the stem f, by an instrument inserted in the room of the operating-tool, substantially as set forth.

11. In a dental handpiece, the combination

with the rigid case A, of the helical spring a, the collar a' having a threaded coupling 2 by which it is connected to the case A and an enlarged end recessed, the collar a² threaded 5 at the back end and fitting within the spring a, the ends of the helical spring being permanently connected to the collars, and a tubular case l screwing at one end upon the collar a² and at the other end fitting within and 10 bearing against the enlarged end of the collar a' and covering the spring a, substantially as and for the purposes set forth.

12. In a dental handpiece, the combination with the sleeve b' and rod h from the dental- 15 engine shaft, of the collar c' having an internal rib 11 and adjacent curved bearing-faces

19 at one end thereof, the head-block o received within the end of the sleeve b' and having curved bearing-faces 18 bearing on the faces 19, the rod n, the head n' thereon and within the collar c' bearing upon the rib 11, a helical spring for drawing the parts into axial line and means for connecting the head n' or rod h or both to the collar c' to cause them to rotate together, substantially as set 25 forth.

Signed by me this 27th day of December, A. D. 1895.

JOHANNES TH. PEDERSÉN.
